UNITED STATES PATENT OFFICE.

HERMAN OTTO, OF JACKSON, MICHIGAN.

CULTIVATOR SHIELD.

1,419,687.

Specification of Letters Patent. Patented June 13, 1922.

Application filed August 24, 1921. Serial No. 494,808.

To all whom it may concern:

Be it known that I, HERMAN OTTO, a citizen of the United States, residing at Jackson, in the county of Jackson and State 5 of Michigan, have invented certain new and useful Improvements in a Cultivator Shield, of which the following is a specification.

This invention relates to a cultivator 10 shield and has for its principal object to provide a shield which will prevent large stones and lumps of dirt from covering the plants after the cultivator has passed over the ground.

15 Another object of the invention is to generally improve upon shields of this character by providing a device which will be of comparatively simple and durable construction and well adapted for the purpose for 20 which it is to be used.

With the above and numerous other objects in view, the invention consists in certain novel combinations and the arrangement of parts as will be hereinafter more 25 fully described and claimed.

In the drawing:-

Figure 1 is an elevational view of the shield, and,

30 Figure 2 is also an elevational view looking from the opposite sides from that shown in Figure 1 and

Figure 3 is a transverse section taken on the line 3—3 of Figure 1 looking in the direction of the arrow.

35 Referring to the drawing in detail it will be seen that 1 designates the shield plate which is provided with the rectangular shaped opening 2 across which are stretched a plurality of bars 3 which have 40 their ends suitably attached to the shield plate 1 adjacent the side edges of the aperture 2. The arm 4 is used in the usual manner for attaching the shield plate to the cultivator.

45 Associated with the shield plate 1 there is provided a slidable closure 5 which is adapted to move vertically adjacent the shield plate 1 and is slidably held in place by a pair of clips 6 which have a sufficient

frictional engagement therewith so as to 50 hold this slidable closure in its adjusted position as may be desired such as is shown in Figures 1 and 2. In use it will be seen that the size of the opening may be regulated by suitable adjustments made with 55 the slidable closure 5 and that the bars 3 extending across the opening will prevent stones and lumps of dirt from passing through the opening so as to fall upon plants as will be readily understood by those skilled 60 in the art.

From the foregoing description taken in connection with the accompanying drawings, the construction and operation of the cultivator shield will be readily understood 65 without a more extended explanation. As numerous changes in form, proportion, and in the minor details of construction may be resorted to without departing from the spirit of this invention, I do not wish to 70 be limited to the construction herein shown and described other than as claimed.

Having thus described my invention what I claim as new is:-

1. A cultivator shield including a shield 75 plate having an opening therein, a plurality of spaced bars extending across the opening, a pair of clips fixed to the shield plate adjacent the opening, and a slidable closure frictionally engaged by the clips so 80 as to be held in desired adjusted position for regulating the size of the opening in the shield plate.

2. A cultivator shield including a shield plate having an opening therein, a pair of 85 clips fixed to the shield plate adjacent the opening, and a slidable closure frictionally engaged by the clip so as to be held in a desired adjusted position whereby the size of the opening in the shield plate may be 90 regulated.

In testimony whereof I affix my signature in presence of two witnesses.

HERMAN OTTO.
